MOUNTING SYSTEM

Edward J. Olowinski, Erie, Pa., assignor to Lord Manufacturing Company, Erie, Pa., a corporation of Pennsylvania

Filed Aug. 8, 1961, Ser. No. 130,171
10 Claims. (Cl. 312—352)

This invention is a mounting system for protecting sensitive equipment from shock, noise, and vibration. One use is in mobile ground equipment for missile control, some of which is so sensitive that when unprotected, its performance is affected by normal conversation in the immediate area.

In the drawing, FIG. 1 is a perspective of the mounting system, FIG. 2 is a section through one of the mountings, FIG. 3 is a section through one of the members for reinforcing and damping the enclosure for the equipment, FIG. 4 is a side view of the mounting system, and FIG. 5 is an end view of the mounting system.

The principal parts of the mounting system consist of an acoustical enclosure 1, a base 2 in the form of two longitudinally extending channels, mountings 3 arranged at the four corners of the enclosure to support the enclosure on the base, and a rack 5 on which the equipment to be protected is mounted.

The acoustical enclosure 1 has spaced inner and outer sheet metal walls 4 and 7 extending around the top, bottom and sides. The ends are closed by panels held in place by nuts 8 and similarly constructed with spaced inner and outer sheet metal walls 9 and 10. The space between the sheet metal walls is filled with an elastomeric foam 11 which fills all void spaces between the walls and provides a damped connection between the sheet metal walls and assists in making the enclosure an effective acoustical shield. Mechanical bracing of the walls of the enclosure is provided by damped structural members 12 extending peripherally around the center of the enclosure and diagonally across the end panels and on either side of the center of the enclosure. These structural members provide reinforcement and at the same time provide reinforcement without creating a metallic path between inner and outer sheet metal walls, and with the introduction of damping into the composite structure.

The structural members 12, as shown in FIG. 3, comprise an inverted channel section 13 and two single sections 14 with one side flange 14a adjacent and extending up along one side of the channel and with the other flange 14b extending outwardly away from the channel. The sides 14a have a plurality of longitudinally spaced slots 15 extending substantially the full height of the sides of the channel. Because of the slots, the angle sections alone have little strength and tend to bend about an axis close to the plane of the flanges 14b. Between each of the flanges 14a and each of the sides of the channel section is a layer 16 of highly damped elastomeric material. This layer is bonded to the outside surface of the sides of the channel and is also bonded to the adjacent surface of the flanges 14a. When installed, the flanges 14b are attached to the inner walls 4 and 9 and the bottom of the channel 13 is attached to the outer walls 7 and 10. The metallic enclosure walls are relatively light and non rigid sheet metal and have numerous natural modes of vibration at frequencies in the sound frequency spectrum and at these frequencies tend to transmit and magnify sound which impinges on the walls. The magnification is increased if any of these frequencies correspond to natural modes of vibration associated with the internal dimensions of the enclosure. The transmission is decreased by two expedients. First, the damped structural members 12 increase the rigidity and raise the natural frequencies of the enclosure

2

above the critical operating frequency range of 0-100 c.p.s. The structural members 12 also provide damping which is effective for frequencies in which the walls of outer and inner shells move in unison as well as for higher frequencies which may produce some independence of motion. The members 12 do not reduce a large scale vibration of the outer shell to smaller motions of the inner. Rather, the members 12 reduce the response of the combined structure, compared to the vibration it would experience if undamped. Hence, conditions inside the box are improved. There is a further attenuation or absorption of acoustical energy by the damping of the structure by the foam 11. Gaskets 18, also of highly damped elastomeric material, are arranged between the removable end panels and the ends of the housing. The result is an acoustical enclosure which has an attenuation averaging 15 db throughout the entire frequency band up to 2500 cycles per second. The attenuation is better than 15 db throughout the critical operating frequency range of zero to 100 cycles per second.

The structural members 12 are described in greater detail in application Serial No. 820,448, filed June 15, 1959. The acoustical enclosure 1 is supported on the base members 2 by mountings 3 arranged at the four corners of the enclosure. Each of these mountings, as shown in detail in FIG. 2, comprises a housing 19 attached to the base channel 2 and an upstanding post 20 extending out through a center opening 21 in the top of the housing and suitably attached to the acoustical enclosure. At the lower end of the post 20 is an enlarged head 22 embedded in a body 23 of highly damped elastomer having upwardly and downwardly extending annular flanges 24 and 25 above and below the head 22 and a radial flange 26 opposite the head. In the normal position, the radial flange 26 is spaced from the vertical wall 27 of a liner 28 of elastomeric material. The lower flange 25 is similarly spaced above a horizontal wall 29 of the liner 28 and the upper flange 24 is spaced below a grommet 30 snapped over the edge of the opening 21 in the top wall of the housing. The liner 27 and grommet 28 are made of the same material as the body 23. While there is normally no contact between the flanges 24, 25 and 26, and the adjacent parts of the housing, upon excessive movement the flanges do make contact and limit the movement. In each case, the contact is between an elastomeric flange (24, 25, 26) and an adjacent elastomeric part on the housing (30, 39, 37). The function of the body 23 and its associated flanges is to limit excessive excursion such as might occur during shock or resonance conditions. The vibration isolation is effected by a coil spring 31 having its lower end seated on a seat 32 on the bottom wall 33 of the housing and having its upper end seated on a seat 34 embedded in and bonded to the under side of the elastomeric body 23. The upper side of the spring seat 34 is spaced below the head 22 so there is no direct metal-to-metal connection through which vibration and noise could be transmitted. The springs 31 are relatively soft so as to provide good vibration isolation. The fact that the flanges 24, 25 and 26 are out of contact with the internal walls 24, 25 and 26 of the housing is desirable for more effective vibration isolation. When the flanges 24 to 26 do come into contact with the interior of the housing it is for the purpose of protecting the supported enclosure 1 from shock.

On opposite side walls of the acoustical enclosure 1 are opposed longitudinally extending channels 35 slidably receiving the rack 5 on which the equipment to be protected is mounted. At the four corners of the rack are rubber mountings 37 which provide a vibration isolating connection from the equipment to the rack. The mountings 37 are primarily for the isolation of high frequency vibration. The rack is held in its operating position by a

releasable catch 38. The removable end panels of the housing have projecting prongs 39 which fit in complementary recesses in the ends of the rack and hold it in place.

A ground strap 40 extends between one of the base channels 2 and the acoustical housing. One wall of the acoustical housing is provided with electrical connectors 41 through which connection is made to the equipment inside the housing.

What is claimed as new is:

1. A mounting system comprising an acoustical enclosure having spaced inner and outer metal walls and a structural connection between the walls including a highly damped elastomer, a rack within and supported by the enclosure, elastomeric mountings on the rack for supporting equipment within the enclosure, a plurality of mountings for supporting the enclosure each comprising a housing having top, bottom and side walls with an opening in the top wall, a member extending out through said opening and connected in load carrying relation into said enclosure, a coil spring having spring seats at upper and lower ends, the lower of the spring seats being on the bottom wall of the housing, a body of highly damped elastomer within the housing having projecting flanges normally spaced from the walls of the housing so as to contact the walls and limit the excursion during shock but not to contact the walls during the normal excursion during vibration, the upper seat being bonded to said body, and said member being embedded in and bonded to said body in spaced relation to said upper spring seat.

2. A mounting system comprising an acoustical enclosure having sound attenuating walls blocking external sounds from the interior of the enclosure, elastomeric mounting means within the enclosure for supporting equipment, said means being proportioned to isolate high frequency vibration from the supported equipment, a plurality of mountings for supporting the enclosure each comprising a soft spring proportioned to isolate low frequency vibrations, a base, a load carrying connection from one end of the spring to the base, a load carrying connection from the other end of the spring to the enclosure, said last mentioned connection including an elastomeric section, and snubbing means having elastomeric parts respectively connected to the base and to the enclosure and spaced from each other during the normal excursion of the enclosure relative to the base during vibration and coming into contact with each other to limit the larger excursion of the enclosure relative to the base during shock.

3. A mounting system comprising an acoustical enclosure having sound attenuating walls blocking external sounds from the interior of the enclosure, vibration isolating means within the enclosure for supporting equipment within the enclosure, a plurality of mountings for supporting the enclosure each comprising a housing having top, bottom and side walls with an opening in the top wall, a member extending out through said opening and connected in load carrying relation into said enclosure, a coil spring having spring seats at upper and lower ends, the lower of the spring seats being on the bottom wall of the housing, a body of highly damped elastomer within the housing having projecting flanges normally spaced respectively from the top, bottom and side walls of the housing so as to contact the walls and limit the excursion during shock but not to contact the walls during the normal excursion during vibration, the upper seat being bonded to said body, and said member being embedded in and bonded to said body in spaced relation to said upper spring seat.

4. A resilient mounting comprising a housing having top, bottom and side walls with an opening in the top wall, a member extending out through said opening and for connection to a load, a coil spring having spring seats at upper and lower ends, the lower of the spring seats being on the bottom wall of the housing, a body of highly

damped elastomer within the housing having projecting flanges normally spaced from the walls of the housing so as to contact the walls and limit the excursion during shock but not to contact the walls during the normal excursion during vibration, the upper seat being bonded to said body, and said member being embedded in said body in spaced relation to said upper spring seat.

5. A resilient mounting comprising a housing having top, bottom and side walls with an opening in the top wall, a member extending out through said opening for connection to a load, a coil spring having spring seats at upper and lower ends, the lower of the spring seats being on the bottom wall of the housing, an elastomeric lining for the housing, a body of highly damped elastomer within the housing having projecting flanges normally spaced respectively from the lining so as to contact the lining and limit the excursion during shock but not to contact the lining during the normal excursion during vibration, the upper seat being embedded in said body, and said member being embedded in said body in spaced relation to said upper spring seat.

6. A resilient mounting comprising a housing having top, bottom and side walls with an opening in the top wall, a member extending out through said opening for connection to a load, a coil spring having spring seats at upper and lower ends, the lower of the spring seats being on the bottom wall of the housing, a body of highly damped elastomer within the housing having a plurality of annular flanges respectively projecting upwardly, downwardly and outwardly from said body and respectively normally spaced from the walls of the housing so as to contact the walls and limit the excursion during shock but not to contact the walls during the normal excursion during vibration, the upper seat being bonded to said body, and said member being embedded in said body in spaced relation to said upper spring seat.

7. A mounting system comprising an acoustical enclosure having sound attenuating walls blocking external sounds from the interior of the enclosure, means within the enclosure for supporting equipment to be protected, a plurality of mountings for supporting the enclosure each comprising a coil spring having spring seats at upper and lower ends, a supporting member carrying the lower spring seat, a body of highly damped elastomer carrying the upper spring seat, a load carrying connection from the elastomer to the enclosure, said connection being spaced from the upper spring seat, and a structure spaced from the elastomer under the normal excursion during vibration and having surfaces coming into engagement with the elastomer under the larger excursions during shock for limiting such excursion.

8. A mounting system comprising an acoustical enclosure having sound attenuating walls blocking external sounds from the interior of the enclosure, means within the enclosure for supporting equipment to be protected, a plurality of mountings for supporting the enclosure each comprising a coil spring having spring seats at upper and lower ends, a supporting member carrying the lower spring seat, a body of highly damped elastomer carrying the upper spring seat, a load carrying connection from the elastomer to the enclosure, said connection being spaced from the upper spring seat, and a structure spaced from the elastomer under the normal excursion during vibration and having surfaces coming into engagement with the elastomer under the larger excursions during shock for limiting such excursion, and a coating of highly damped elastomer on said surfaces for absorbing energy of impact.

9. A mounting system comprising an acoustical enclosure having sound attenuating walls blocking external sounds from the interior of the enclosure, means within the enclosure for supporting equipment to be protected, vibration isolating means for supporting the enclosure comprising a soft spring means proportioned to isolate

low frequency vibrations, a base, a load carrying connection from one end of the spring means to the base, a load carrying connection from the other end of the spring to the enclosure, said last mentioned connection including an elastomeric section, and snubbing means including elastomeric parts respectively connected to the base and to the enclosure and spaced from each other during the normal excursion of the enclosure relative to the base during vibration and coming into contact with each other to limit the larger excursion of the enclosure relative to the base during shock.

10. A resilient mounting comprising a coil spring having spring seats at upper and lower ends, a supporting member carrying the lower spring seat, a body of highly damped elastomer carrying the upper spring seat, a supported member, a load carrying connection from the elastomer to the supported member, said connection being

spaced from the upper spring seat, and a structure spaced from the elastomer under the normal excursion during vibration and having surfaces coming into engagement with the elastomer under the larger excursions during shock for limiting such excursion.
